UNITED STATES PATENT OFFICE.

JULIO PINAL, OF BROOKLYN, NEW YORK.

GENERATOR.

1,288,171.

Specification of Letters Patent.

Patented Dec. 17, 1918.

Application filed March 11, 1918. Serial No. 221,688.

To all whom it may concern:

Be it known that I, JULIO PINAL, a citizen of Mexico, residing at Brooklyn, in the county of Kings and State of New York, have invented certain new and useful Improvements in Generators, of which the following is a full, clear, and exact description, such as will enable others skilled in the art to which it appertains to make and use the same.

This invention relates to methods and apparatus for generating heat, and with respect to its more specific features, to methods and apparatus of the character referred to providing for the combustion of a liquid fuel and the utilization of the heat of combustion for gasifying the fuel and giving pressure to the resultant gas.

One of the objects of the invention is the provision of an efficient method for generating heat and utilizing the possibly otherwise waste heat by causing it to assist in the gasification of the fuel.

Another object of the invention is the provision of a practical method of the character referred to and involving the giving of pressure to the gas and the flame resulting from its ignition.

Another object of the invention is the provision of a simple and efficient apparatus for gasifying liquid fuel and conserving the heat energy resulting from the combustion of the gas.

Another object of the invention is the provision of a practical apparatus for generating heat from liquid fuel and for the control of the feed of fuel to modify the character of the heat.

Another object of the invention is the provision of a simple and inexpensive apparatus for the gasification of liquid fuel and the combustion of the resultant gas so arranged that the heat of combustion may be utilized in gasifying the liquid fuel, and so that the apparatus may be readily taken apart, assembled and applied where desired.

Other objects will be in part obvious and in part pointed out hereinafter.

The invention accordingly consists in the several steps and the relation and order of one or more of such steps with relation to each of the others thereof, and in the features of construction, combinations of elements and arrangement of parts, which will be exemplified in the process hereinafter disclosed and the construction hereinafter

set forth, and the scope of the application of each of which will be indicated in the following claim.

In the accompanying drawings forming part of this specification, wherein is shown one of various possible embodiments of this invention,—

Figure 1 is a perspective view of an apparatus embodying the invention; and

Fig. 2 is a longitudinal sectional view of a portion of the apparatus, with the head of the generator slightly spaced from the rest of the casing.

Referring now more specifically to the drawings, the letter *a* indicates generally a generator, through which liquid fuel is adapted to pass, and in its passage becomes gasified or vaporized; a source of liquid fuel supply for the generator is indicated by the letter *b*, and at *c* is shown a fuel burner so disposed that the burning of the fuel thereat heats the generator.

The numeral 1 indicates a pipe adapted to conduct liquid fuel from the source of liquid fuel supply or container *b* to the generator, and the numeral 2 indicates a pipe adapted to conduct the gasified or vaporized fuel from the generator to the burner or burners *c*.

In the present embodiment the generator comprises a casing having passageways adapted to conduct the fuel in a circuitous course through the generator. The numeral 3 indicates a hollow metallic body or outer metallic tube preferably permanently closed at one end, as at 4, and at its opposite end having a flaring inner wall surface 5, and an outwardly extending flange 6, provided with bolt openings. The numeral 7 indicates a member removably mounted in the body and dividing the same longitudinally into inner and outer passageways. In the present embodiment this member comprises an inner metallic partition or tube having a helical groove 8 on its outer face, the exterior face of the member 7 being designed to nicely fit the inner wall of the tube 3 so that the helical groove of the member 7 cooperates with the inner wall of the member 3 to form a helical outer passageway, as illustrated, surrounding the said inner passageway or main passageway 9 of the inner metallic tube. One end of the helical passageway referred to is in communication with the passageway 9, this communication being effected, in the present embodiment, by spacing the end 4 of

the body member 3 from the adjacent end of the tubular member 7, as indicated at 10, where a chamber is formed into which the helical passageway opens. The opposite end 5 of the helical passageway is in communication with the pipe 1, whence the fluid is received from the container *b*, and at this end the inner and outer passageways referred to are sealed from direct communication with each other. To this end the tubular member 10 7 may be formed as an integral part of a head 11 extending transversely across the end of the outer tubular member 3 by means of the bolts 12 secured by wing nuts 13 so that these parts may be readily uncoupled or secured together as may be desired. The head 11 may be provided with a tapered lateral wall or shoulder 14 to coöperate with the flaring surface 5 of the outer tubular member 15 20 to form an air-tight joint when the bolts referred to are set up. In the present embodiment the inner passageway 9 is larger in cross section than the outer passageway 8 and may be filled with a gas-cleaning material, which at the same time is a heat-conducting material, as for instance, steel wool. The numeral 16 indicates an opening through the head 11 and communicating with the outer or helical passageway 8 or 25 30 with the space between the end of said passageway, and the head 11 and the pipe 1 conducts liquid fuel from the container *b* to this opening, as illustrated, by gravity. Another opening 17 through the head 11 communicates with the inner passageway 9 and delivers fuel from the generator to the pipe 2 leading to the burners *c*. Suitable valves may be interposed at various points for controlling the supply of fuel to the generator 35 40 and the supply of gas from the generator to the burners. Such valves may be ordinary hand-operative liquid controlling and gas controlling valves, such as are indicated generally by the numerals 18, 19, 20.

45 To start the apparatus, a lamp or torch or other suitable source of heat is applied to the outer wall of the generator, and the generator heated sufficiently to cause the vaporization or gasification of the liquid fuel supplied from the container *b*. Upon opening the valve 18, the liquid fuel will flow to the outer or helical passageway of the container, and will flow through said passageway, the head of the liquid fuel supply being sufficiently great. As the liquid fuel flows 50 55 through the helical passageway it is heated and eventually becomes vaporized or gasified and emerges as a gas or vapor into the chamber 10, whence it passes through the inner passageway 9 to the pipe 2, and by way of said pipe to the burners *c*. The resultant gas or vapor may be ignited at the burners and will serve to heat the generator so that after gas has once been supplied to 60 65 the burner, the apparatus continues auto-

matically to gasify liquid fuel and supply the burner with gasified or vaporized fuel so long as there is a sufficient head of liquid fuel to supply the generator or until the burner is extinguished. Should the burner be extinguished, the apparatus may be started by merely again igniting the gas, provided it has not been permitted to stand so long that the generation of vapor has ceased. In this wise it will be perceived that there has been devised a method of generating heat by burning a gasified liquid fuel, as at the burner *c*, expending a portion of the heat of combustion in gasifying the liquid to be burned, as by heating the generator by the flame or burner, the steps of burning the gasified fuel and expending a portion of the heat of combustion being correlated, by conducting the gasified fuel to the place to be burned, that is from the generator to the burner *c*.

It will be noted that the within described invention provides a heating apparatus which is capable of extensive use, and is at the same time inexpensive, simple in construction, economic to operate, and easy to regulate. The generator is air-tight and should be sufficiently strong to withstand the pressure of the gas generated therein, which pressure will increase as the temperature increases so that an efficient pressure of the gas will ensue, sufficient to effectively supply the burners and cause the gas to issue in a strong stream therefrom, and thereby increase or decrease the intensity of the heat of combustion in accordance with such factor. With a sufficient supply of air for combustion an intensely hot flame may be produced, and it is found that the apparatus operates with practically no smoke or residue. Certain impurities of the fuel are removed by the cleaning material in the inner passageway, and much of the heat of combustion is conserved by reason of the reverse flow of fuel in its passage through the generator, it being noted that the fuel passes through the helical passageway in one direction generally longitudinally of the generator, and returns through the inner passageway, which is within the helix, so that the structure is such as to efficiently conserve the primary heat. Various fuels may be employed, such as gasoline, or light crude oils, alcohol, etc. The apparatus is capable of a wide variety of uses. The generator and burner may be placed in the firepot of a stove as a substitute for solid fuel, or the apparatus may be employed to heat boilers, ranges, etc. Thus by the above described construction are accomplished, among others, the objects hereinbefore referred to.

As many changes could be made in carrying out the above process, and in the above construction, and many apparently widely different embodiments of this invention

could be made without departing from the scope thereof, it is intended that all matter contained in the above description or shown in the accompanying drawings shall be interpreted as illustrative and not in a limiting sense.

It is also to be understood that the language used in the following claim is intended to cover all of the generic and specific features of the invention herein described and all statements of the scope of the invention, which, as a matter of language, might be said to fall therebetween.

Having described my invention, what I claim as new and desire to secure by Letters Patent is:

A generator of the character described, comprising, in combination, an outer metallic tube, an inner metallic tube having a helical groove in its outer surface coöperating with the outer tube to form a helical

passageway around the opening of the inner tube, said outer tube being closed at one end, and at this end spaced from the adjacent end of the inner tube, and at its opposite end having a flaring inner wall surface, said inner tube having a transverse head disposed across the other end of said outer tube and bolted to the latter tube, and having an opening communicating with the opening through the inner tube and another opening communicating with said helical passageway, said head having a tapered wall coöperating with said flaring surface to form an air-tight joint.

In testimony whereof I affix my signature, in the presence of two witnesses.

JULIO PINAL.
